(57) **CLAIM**

We claim the ornamental design for the tibial implant components, as shown and described.

DESCRIPTION

FIG. 1 is a front perspective view from above of the claimed design according to one embodiment;

FIG. 2 is a front view of the claimed design of FIG. 1; FIG. 3 is a rear side view of the claimed design of FIG. 1; FIG. 4 is a right side view of the claimed design of FIG. 1; FIG. 5 is a left side view of the claimed design of FIG. 1; FIG. 6 is a top view of the claimed design of FIG. 1; FIG. 7 is a bottom view of the claimed design of FIG. 1; and, FIG. 8 is a front perspective view from below of the claimed design of FIG. 1.

(Continued)

The ornamental design which is claimed is shown in solid lines in the drawings. The broken lines in the drawings are for illustrative purposes only and form no part of the claimed design.

1 Claim, 5 Drawing Sheets

Related U.S. Application Data

continuation-in-part of application No. 13/340,645, filed on Dec. 29, 2011, now Pat. No. 8,911,501, and a continuation-in-part of application No. 13/340,636, filed on Dec. 29, 2011, now Pat. No. 9,649,195.
